His Attorney.

UNITED STATES PATENT OFFICE.

JOHN H. DORAN, OF SCHENECTADY, NEW YORK, ASSIGNOR TO GENERAL ELECTRIC COMPANY, A CORPORATION OF NEW YORK.

ELASTIC-FLUID-TURBINE-DRIVEN SET.

1,362,401.

Specification of Letters Patent. Patented Dec. 14, 1920.

Application filed May 17, 1920. Serial No. 381,920.

To all whom it may concern:

Be it known that I, JOHN H. DORAN, a citizen of the United States, residing at Schenectady, in the county of Schenectady, 5 State of New York, have invented new and useful Improvements in Elastic-Fluid-Turbine-Driven Sets, of which the following is a specification.

The present invention relates to elastic 10 fluid turbine driven sets, and more particularly to sets comprising a turbine of the radial flow type wherein the rotor comprises two oppositely rotating members, located in a casing which is rigidly supported, said 15 members driving separate machines which are located on opposite sides of the turbine casing and have their casings spring supported and directly connected to the turbine casing.

20 The object of my invention is to provide an improved structure and arrangement in a set of this character, and for a consideration of what I believe to be novel and my invention, attention is directed to the accompanying description and the claims appended thereto.

In the drawing, Figure 1 is an outline of a turbine driven set embodying my invention; Fig. 2 is a view on a larger scale and 30 partly in section of a part of the set shown in Fig. 1; and Fig. 3 is a view similar to Fig. 2, of a modification.

Referring to the drawing, 5 indicates the casing of an elastic fluid turbine of the 35 radial flow type having a wall 6 which defines an exhaust opening. The turbine casing is rigidly supported, such support being shown as comprising a condenser 7 having an inlet conduit 8 on which wall 6 rests and 40 to which it is bolted. The turbine is thus rigidly supported on the condenser, and the latter in turn is mounted on a foundation which may be of concrete. The turbine is of the radial flow type and has oppositely 45 rotating rotors which are coupled directly to driven machines 9 and 10 shown as being electric generators. Generators 9 and 10 are spring supported on columns 11 which at 50 their lower ends rest on spring 12 carried on brackets 13 projecting from opposite sides of the condenser casing. 14 indicates an oil tank carried by the one generator casing, and 15 indicates conduits for cooling air for the generators. Formed integral 55 with the turbine casing on opposite sides

thereof are bolting flanges 16, and the generator casings are bolted directly to such flanges through the intermediary of rings 17 which have flanges 18 at their two ends. 60 19 indicates the bolts which connect flanges 18 to the bolting flanges 16 on the turbine casing and flanges 20 on the generator casings.

During the operation of an elastic fluid 65 turbine the casing is subjected to wide variations in temperature while starting up and with changes in load which cause sudden expansions and contractions of the casing. On the other hand, the generator casing remains at a substantially constant temperature due principally to the system of cooling 70 therefor. The turbine casing must therefore be able to expand and contract without setting up too great stresses at the points of connection to the generator. Also 75 in a set in which the generator or generators are spring supported vibrations may be set up by the generator or generators and it is necessary that the turbine casing be protected against such vibrations. The turbine 80 and generator casings are made of cast iron and according to my invention whenever I utilize separate rings 17 for connecting them I am enabled to make such rings of cast steel 85 which gives ample strength to the connection between the turbine and generator casings, and avoids the necessity of making the entire turbine casing of cast steel as would otherwise be the case and which would very 90 largely increase the cost.

In order to reduce the stresses in the rings 17 caused by uneven heating and the slow transfer of heat from the turbine through rings 17 to the generator, I provide slots 21 which extend from points in flanges 16 part 95 way through rings 17. These serve to prevent the tangential stresses due to expansion from becoming too great.

In Fig. 3 I have shown an arrangement similar to that shown in Fig. 2 except that 100 rings 17*, which correspond to rings 17 of Fig. 2, are provided with internal flanges 18* which are bolted directly to the turbine casing by bolts 19* which are preferably tapered to prevent leakage, and with internal flanges 105 18* which are bolted to flange 20* on the generator casing. Also ring 17* has spaced openings 22 and slots 21* which correspond to the slots 21 of Fig. 1.

In accordance with the provisions of the 110

patent statutes, I have described the principle of operation of my invention together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. In combination, a rigidly supported turbine casing, a yieldably supported casing, and a separate ring which is fastened to and connects said casings together whereby said ring may be made of a material stronger than that of which the casings are made.
2. In combination, a condenser, a turbine rigidly mounted thereon, a driven machine having its casing yieldably supported on the condenser casing, and a separate ring which is fastened to and connects said turbine and driven casings together.
3. In combination, a turbine which is rigidly supported, a driven machine on each side of the turbine, the casings of said driven machines being yieldably supported, and

separate rings which are fastened to and connect said driven machine casings to the turbine casing.

4. In combination, a rigidly supported turbine casing, a yieldably supported casing, and a separate ring which is fastened to and connects said casings together, whereby said ring may be made of a material stronger than that of which the casings are made, said ring being provided with spaced slots which extend from the one edge of the ring part way across it.

5. In combination, a condenser, a turbine having oppositely rotating rotors, said turbine being mounted directly on the condenser with its exhaust opening fastened to the inlet opening of the condenser, driven machines located on opposite sides of said turbine and yieldingly supported on said condenser, and separate rings having their ends fastened to the turbine casing and to the casings of said driven machines.

In witness whereof I have hereunto set my hand this 15th day of May 1920.

JOHN H. DORAN.
